SELF-SHARPENING SAFETY RAZOR

James B. Brockhurst, Red Bank, N. J.

Application May 19, 1942, Serial No. 443,555

15 Claims.

(CL. 30—36)

The present invention relates to safety razors and more particularly to improvements in self-sharpening safety razors and blades therefor.

An important object of the invention is to provide a self-sharpening safety razor possessing new and advantageous features. Another important object is to provide a new and advantageous safety razor blade particularly adapted for use in the self-sharpening safety razor of the present invention. Another object is to provide a new and advantageous self-sharpening safety razor in which the edges of the blade are guarded at all times during the sharpening operation. Another object of the invention is to provide a new and advantageous self-sharpening safety razor in which the blade is directly and accurately centered in the razor preparatory to use. Another object of the invention is to provide a new and advantageous form of safety razor in which a cap carrying sharpening material can easily be removed, thus facilitating blade-changing and changing of caps in which a cap carrying sharpening material of a certain degree of fineness may readily be replaced by a cap provided with sharpening material of a different degree of fineness. A further object is to provide a razor blade open at its interior to receive therethrough members for holding in fixed relation razor parts at opposite sides of the blade while permitting transverse movement of the blade with reference to said parts to an extent determined by engagement of said members by opposite interior abutting edges of said blade.

Other objects, features and advantages will appear upon consideration of the following detailed description and of the drawing in which:

Fig. 1 is a sectional view of an illustrated form of the invention taken along the plane through the axis of the razor and centrally positioned with respect to the razor head;

Fig. 2 is a fragmentary view looking at one end of the razor head;

Fig. 3 is a section of the head position taken along a plane perpendicular to that of Fig. 1, showing the blade shifted to one side;

Fig. 4 is a section taken along a plane perpendicular to that of Fig. 3, the parts being positioned to shift the blade;

Fig. 5 is a plan view of the concave under surface of the cap;

Fig. 6 is a top plan view of the main or fixed plate of the head;

Fig. 7 is a section taken along the line 7—7 of Fig. 1;

Fig. 8 is a section taken along the line 8—8 of Fig. 2; and

Fig. 9 is a section taken along the line 9—9 of Fig. 1.

Referring to the drawing, the illustrated embodiment of the invention includes a head member or plate 10 fixed on the upper end of a tubular member tube 11 which forms part of a handle 12. At the lower side of said head plate 10 is a member or plate 13 movable transversely of head plate 10 and which may serve both as an actuating plate or member for a blade 14 and also as a guard for the edges of the blade. As shown, for example, in Figs. 1, 2, and 3, the guard plate 13 or guard 13 extends somewhat beyond the edges of the blade 14 and the edges of the guard plate are turned back in a manner somewhat similar to that of the usual guards.

The blade-actuating plate or guard may be 20 slidably mounted on the fixed head plate 10 and to this end the ends of the plate 10 may be beveled downwardly and outwardly and may fit into corresponding recesses or grooves 15 in upright arms 16 preferably integral with the guard and extending upwardly from the central parts of the ends, thus providing one form of tongue and groove sliding connection. These arms engage in centrally positioned recesses or notches 16a in the ends of the blade 14 to center the blade on the 30 guard 13, and preferably are tapered in width to assure engagement with both ends of each of said recesses. Obviously the blade ends might be extended and the recesses 16a closed to form slots.

The blade 14 is positioned between the head plate 10 and a cap 17 which fits between the upper ends of the upright arms and is held against transverse movement with respect to the head plate by means of a central stem 18 projecting from the cap into the upper end of the tubular member 11 and studs 19 with ends, reduced as by tapering the same, extending downwardly through openings 20 in the blade and openings 21 in the head plate 10. The studs 19 are provided at suitable points with beveled seats 22 adapted to rest on countersunk seats 23 in head plate 10. Also the stem 18 is provided with a beveled seat 27 adapted to rest on a countersunk seat 28, in the top of tube 11. As indicated in Fig. 9, the length of the sharpening strokes of the blade is determined by engagement of the stem 18 and studs 19 with abutting edges 28a at the ends of the slots 20 in the blade 14.

The cap 17 is connected to the handle 12 by means of a screw connection between the stem 18 and a rotatable spindle or rod 29 extending

through the tube 11 of the handle and provided at its outer end with a head or finger piece 30 engaging the outer end of the tube 11. As illustrated, the stem 18 is threaded into the enlarged end of the spindle 29, which enlarged end is held in position longitudinally of the handle 12, between a shoulder 31 formed by an increase in the internal diameter of the tube 18 and a tube 32 pressed into tube 11, said spindle 29 being rotatable in tube 32. In this connection it may be stated that the studs 19 are long enough as compared with other parts, so that when the cap 17 is placed over the blade, the studs 19 will pass through the openings 21 in the head plate before the screw connections between stem 18 and the upper end of the spindle 29 are established. The lower or inner face of the cap 17 is concave transversely and when the cap is drawn toward the head 10 by turning the finger-piece head 30, the blade is flexed due to pressure by the edges of the cap 17, over the downwardly and outwardly inclined surfaces at the longitudinal edges of said head member 10. In this flexing the central part of the blade will be raised and the ends of recesses 16a will be brought closer together and kept in engagement with the edges of tapered arms 16.

In order to effect a sharpening action, the cap 17 may have sharpening material 33 at its lower face. As illustrated, the sharpening material is in the form of a sheet or plate covering the entire lower surface of the cap. However, the sharpening material may be used only at the edges of the cap, or the whole cap may be made of sharpening material.

In addition to openings 34 through which studs 19 pass, the blade-actuating plate or guard 13 may be provided with a circular opening 35 through which passes the tube 11 containing the stem 18 of the cap 17, the diameter of the opening being sufficient to permit movement of the guard through a distance corresponding to the desired lateral movement of the blade 14. For cooperation with another part to lock plate 13 against lost motion, as will be described more fully hereinafter, circular opening 35 is tapered so as to have its greatest diameter at the lower face of plate 13. Just outside of the circular opening toward one end of the plate 13 is a finger 36 which extends downwardly and then inwardly toward the tube 11, and may serve both for guard-actuating and for guard centering.

The actuation, centering, and locking of the guard 13 against lost motion may be controlled by a finger piece 37 slidable on the tube 11 and having at its bottom a sleeve 38 slidable on an external finishing sleeve 39 fixed on tube 11 of the handle and with one end in engagement with the head 30 on the spindle 29 which effects tightening or loosening of the cap 17. Preferably sleeve 39 is formed of ornamental plastic material.

Inside the sleeve 38 is a spring 40 interposed between the sleeve 39 and the body of the finger piece 36, to urge the finger piece toward the guard 13 and hold the guard against lost motion by pressing a tapered or conical outer surface on the upper part of the finger piece into effective locking engagement with the tapered surface around the circular opening 35 in the guard 13. The upper part of the finger piece 37 which has the tapered outer surface may be in the form of an upwardly projecting circular flange 41 having in its top a centering notch 42 to cooperate with finger 36 in centering the guard before the flange is seated in the circular opening 35 to

lock the guard against lost motion, and also an operating notch 42 which may be brought into a position to receive the finger and enable the finger piece 37 to shift the guard. Of course the centering notch is deep enough so that the finger 36 will not interfere with the seating of the flange in the circular opening and the operating notch is so shallow as to prevent such seating. Furthermore the operating notch increases in width from the outer to the inner surface of the flange to avoid cramping of the parts while maintaining a close connection therebetween. The bottom of the operating notch 43 serves as a seat 44 to engage finger 36.

15 The sharpening operation may be carried out by moving the finger piece 37 downwardly until the flange 41 clears the centering notch 42 and by turning the finger piece 37 so that the finger 36 engages the top of the flange. Then when the 20 finger piece is turned through 180°, the finger 36 will snap into the operating notch 43 and engage the seat 44 which will prevent the flange from coming into locking engagement with the guard plate. When the sharpening operation is 25 finished, the finger piece 37 is moved down to disengage the finger 36 from the operating notch 43 and then turned until the finger snaps into the positioning notch, or centering notch, 42 and locks the finger piece 37 in the central opening 30 in the guard plate 13.

As indicated particularly in Fig. 9, the blade 14 is certain to be in proper alignment with reference to the head plate 10 and cap 17 as a result of the abutting ends of the slots 29 being brought into engagement with the stem 18 of the cap 17 and with the studs 19. This aligning of the blade will also effect proper alignment of the guard which is closely connected to the aligned blade.

40 It should be understood that the blade 14 will be flat on the head plate 10 when first placed in the razor and will be accurately positioned by the arms 16 engaging both ends of the end notches 16a. When, however, the cap 17 is drawn toward the head plate, the blade 14 will be flexed and the central portion will be raised. The actual distance between opposite ends of the end slots or notches will thus be decreased, but the arms become correspondingly narrower 45 so that the close fit of the arms in the notches is maintained. Although head plate 10 is illustrated as permanently fixed on the end of tube 11 of the handle, it is obvious that the head plate may be removably mounted on the tube 11.

50 As indicated in Figs. 2 and 3, the left edge portion of the blade 14 when the blade is moved to the right, is engaged from above by the sharpening material 33 and from below by the head plate 10, thus acting to remove, as indicated in Fig. 2, any soap, lather, etc., which might have 55 accumulated on the blade.

It should be understood that the blade 14 may also be operated manually without use of the finger piece 37. For example this operation may be effected by holding in the right hand the razor handle and also the finger piece 37 in retracted position to free the plate or guard 13, and by moving the blade 14 back and forth by grasping the projecting end portions of the blade or the 60 upright arms 16 of the guard 13. Of course the finger 36 might be permitted to engage the upper edge of the flange 41 when the finger piece 37 is turned 90° from its Fig. 7 position. Then movement of the blade 14 would involve sliding of the 65 finger 36 along the top of the flange 41.

It should be understood that various changes may be made and that certain features may be used without others, without departing from the true scope and spirit of the invention.

What I claim is:

1. In a self-sharpening safety razor, a cap having sharpening means at its inner face, a handle, a head plate fixed on one end of said handle, a blade adapted for transverse movement, a guard beneath said head plate and movable transversely thereof, connections between said guard and said blade to actuate the latter, means for centering said guard, means for actuating said guard to actuate said blade, a finger piece on said handle adapted to render either said centering means effective or such guard actuating means effective, and means including said handle for flexing and holding said blade between the cap and the head.

2. In a self-sharpening safety razor, a handle, a head plate fixed on one end of said handle, a blade, a cap having sharpening material thereon, a guard beneath said head plate and mounted for movement transversely thereof, a blade between said cap and head plate, connections between said guard and said blade to actuate the latter, means for drawing said cap and head plate together to flex and hold the blade, a finger piece rotatable and slidable on said handle and spring-pressed toward said guard, centering means comprising a finger projecting from said guard and a centering notch in the top of the finger piece to receive said finger for centering, and guard actuating means including an operating notch of less depth in the top of said finger piece to receive said finger to enable actuation of the guard by turning the finger piece.

3. In a self-sharpening safety razor, a cap with sharpening means thereon, a handle, a head plate fixed on one end of said handle, a blade between said cap and head plate, a guard plate movable transversely of said head plate, means for forcing said cap and head plate toward each other to flex and hold the blade, connections between said guard plate and to said blade to actuate the same, means for centering said guard, means for locking said guard to prevent lost motion, means for actuating the guard transversely, and a finger piece movable to one position to render said actuating means effective and to another position to render first such centering means effective and then such locking means effective.

4. In a self-sharpening safety razor, a cap with sharpening material thereon, a handle, a head plate fixed on one end of said handle, a blade between said cap and head plate, a guard beneath said head plate and movable transversely thereof, connections between said guard and said blade to actuate the latter, means for drawing said cap and head plate toward each other, a finger piece rotatable and slidable on said handle and spring pressed toward said guard, blade operating means including a finger projecting from said guard and an operating notch in the top of said finger piece to receive said finger for operating the guard from the finger piece, and lost motion preventing means effective to hold said guard positioned for shaving.

5. In a self-sharpening safety razor, a cap with sharpening material thereon, a handle, a head plate fixed on one end of said handle, a blade between said cap and head plate, a guard beneath said head plate and movable transversely thereof, connections between said guard and said

blade to actuate the latter, means for drawing said cap and head plate together to flex and hold the blade, a finger piece rotatable and slidable on said handle and spring pressed toward said

5 guard, means for preventing lost motion including a tapered circular friction seat at the interior of a central circular opening in said guard and a corresponding friction seat at the exterior of the upper end of the finger piece, centering means 10 comprising a finger projecting from said guard adjacent said central opening and a notch in the top of the finger piece to receive said finger for centering purposes and to permit further movement to render effective such lost-motion-preventing means, and guard actuating means 15 including a notch in the top of said finger piece adapted to receive said finger for operating connection and to limit the inward movement to prevent engagement between the friction seats.

6. A safety razor comprising a cap with sharpening means thereon, a head plate, a handle comprising a central tube with its upper end fixed in a central opening in said head plate, a guard beneath said head plate and having its ends carried around the ends of said head plate in a tongue and groove sliding connection, a blade between said cap and said head plate, means connecting said blade to said guard to move therewith, means for drawing said cap and head plate toward each other to flex and hold the blade, a finger piece rotatable on said handle and slid- 20 able thereon, and cooperating parts between said guard and finger piece whereby the finger piece may be retracted, turned to a certain position, and advanced to establish a connection for moving the guard and blade transversely of the head plate, or to another position where advance of the finger piece will first center the blade and then lock it in position.

7. In a safety razor of the class described, the combination of a head plate, a transversely movable guard at the lower side of said head plate, a blade above said head plate having transverse-positioning and actuating notches in its ends and arms projecting upwardly from the ends of said guard and fitting between the ends of said notches, the arms being tapered to assure contact with both ends of each notch.

8. In a safety razor of the class described, the 25 combination of a head plate, a transversely movable guard at the lower side of said head plate, a blade above said head plate having transverse-positioning and actuating notches in its ends, arms projecting upwardly from the ends of said guard and fitting between the ends of said notches, the arms being tapered to assure contact with both ends of each notch, a cap with sharpening material thereon over said blade with its ends engaging the inner faces of said arms, and means for drawing said cap and head plate toward each other to flex the blade and hold the parts together.

9. In a safety razor of the class described, the combination of a head plate, a transversely movable guard at the lower side of said head plate, a cap with sharpening material thereon, a blade between said head plate and said cap having transverse-positioning and actuating notches in its ends, and upwardly projecting tapered arms 30 at the ends of said guard engaging the ends of said head plate in a tongue and groove connection and fitting at all times in said notches in the blade due to the taper of said arms, and means to draw the cap and head plate toward each other and flex and hold the blade.

10. A blade for a self-sharpening razor, having elongated centering notches at its ends for positioning the blade both longitudinally and transversely on blade-actuating means, and transverse slots with stop edges at opposite ends of the slots for engagement with razor parts to limit the movement of the blade and assure proper alignment thereof.

11. In a self-sharpening razor, a cap having sharpening means at its longitudinal edges, a head plate, a guard movable transversely of said cap and head plate, a blade between said cap and the head plate and guard, means including a razor handle for flexing said blade between the cap on one hand and the guard and head plate on the other, and means connecting said blade to said guard for movement therewith transverse to the cap to cooperate with said sharpening means.

12. In a self-sharpening safety razor, a cap having sharpening means at its longitudinal edges, a head plate, a guard movable transversely of said cap and head plate, a blade between said cap and head plate and guard, means including a razor handle for flexing said blade between the cap on one hand and the guard and head plate on the other, means connecting said blade to said guard for movement therewith transverse to the cap to cooperate with said sharpening means, and means including a finger piece on said handle for centering said guard and blade or for actuating them transversely of the cap and head.

13. In a razor of the class described, a cap having sharpening material at the longitudinal edges of its inner face and having studs projecting therefrom, a head having openings in which

said studs fit and prevent relative transverse movement of said cap and head, a blade between said cap and head and having transverse slots receiving said studs and also end openings, a guard at the inner face of and slidably mounted for movement transverse to said head, said guard having at its ends upwardly extending arms fitting in said end openings of the blade whereby transverse movement of the guard will effect corresponding movement of the blade, and means for pressing said cap toward said head to flex the blade, said arms being tapered so as to fit the end openings when the blade is flat or when it is flexed and the distance between the ends 15 of said openings is shortened.

14. In a safety razor, the combination of a head plate, a cap provided with sharpening means, means extending between said head plate and cap to prevent relative transverse movement, a blade between said cap and head plate open centrally to receive the means between said head plate and cap and permit transverse movement of the blade for sharpening on said sharpening means, and means for flexing said blade 20 and holding it in centered position, said blade having end portions projecting beyond the ends of the head plate and the cap and adapted to be grasped by the hand for hand manipulation.

15. A blade for a self-sharpening razor having centering openings at opposite sides of the middle of the blade for positioning the blade both longitudinally and transversely on blade actuating means and an open interior having stop edges at opposite sides for engagement with razor 30 parts to limit the movement of the blade and assure proper alignment thereof.

JAMES B. BROCKHURST.
